UNITED STATES PATENT OFFICE.

ADELMER A. BISHOP, OF RACINE, WISCONSIN; EMMA MAUDE BISHOP ADMINISTRATRIX OF SAID ADELMER A. BISHOP, DECEASED.

TRUCK.

Application filed March 8, 1921. Serial No. 450,609.

To all whom it may concern:

Be it known that I, ADELMER A. BISHOP, a citizen of the United States, and resident of Racine, in the county of Racine and State 5 of Wisconsin, have invented certain new and useful Improvements in Trucks; and I do hereby declare that the following is a full, clear, and exact description thereof.

This invention relates to an improved 10 truck which is primarily designed for use in laundries, but it is obvious that it is equally well adapted for use wherever it is desirable to use a truck having a plurality of compartments for receiving separate batches of 15 material and keeping the same separate from each other.

In most modern laundries which make a specialty of family washings, instead of marking each individual piece with the name 20 or number of the owner, it is now the prevailing custom to wash each family package in a separate batch, thus eliminating the time and expense incident to marking and sorting. In carrying out the process according 25 to this method it is necessary, of course, to keep the different batches separate throughout the various steps of washing, rinsing, drying, mauling and the like.

With the above facts in mind it is the 30 primary object of the invention to provide a truck for transferring the batches from one machine to another which shall have a plurality of compartments most conveniently arranged for the purpose specified.

It is more particularly the object of the 35 invention to provide a truck body of this kind, having means for covering all but one of the compartments, and wherein only one compartment can normally be uncovered at a time.

With the above and other objects in view, the invention resides in the novel features of construction, as illustrated in the accompanying drawings, in which:

Figure 1 is a plan view of one form in 45 which my invention may be embodied.

Figure 2 is a vertical sectional view on the line 2—2 of Figure 1.

Referring more specifically to the drawings, the numeral 1 designates the body of 50 my improved truck, which is mounted on the wheels 2. This body constitutes a receptacle which is divided into a number of

compartments as illustrated in Figures 1 and 2. The body is in the form of a regular 55 prism, and is divided by the partitions 3 which extend from the axis of the prism to the edges thereof, thus forming a plurality of triangular prismatic compartments. Each of these partitions except one, is provided 60 with a cover 4, which is hinged thereto at 5. Thus it will be seen that each of the covers may be swung so as to cover either one of the compartments adjacent to the partition upon which the cover is hinged. 65

From the foregoing description it will be seen that I have provided a practical and convenient device for handling a number of different batches which may be kept separate from each other. It will also be seen 70 that one of the compartments is always open ready to receive the articles to be washed, and another compartment cannot be opened without closing the one which has previously been opened, thus there is no chance of getting the different batches mixed. 75

The form illustrated and described is particularly serviceable due to the fact that the flat sides allow the device to be moved up flush against the machine from which the 80 articles are to be removed, leaving no space through which they may drop, or in which they may become entangled.

It will, however, be understood that the 85 invention, as shown, is merely for the purpose of illustration, and that various modifications may be made within the scope of what is claimed without departing from the spirit of the invention.

I claim as my invention:

1. A truck body having a plurality of vertical partitions of equal width extending radially from the center thereof, and dividing said body into a series of equal compartments, all but one of said partitions 95 having a cover hinged to its upper edge, said cover being movable on its hinge to cover either of the compartments adjacent thereto with its free edge portion resting on the partition between the compartments so covered and an adjoining compartment. 100

2. A truck body in the shape of a regular prism and having bottom and side walls, partitions extending radially from the axis of the prism to the side edges thereof, and 105 dividing the same into a series of equal tri-

2
angular prismatic compartments, all but one of said partitions having a cover in the shape of isosceles triangle, one leg of which is hinged to the upper edge of the partition, 5 said cover being movable on its hinge to cover either of the compartments adjacent thereto with the other leg of the triangle resting on the partition between the com-

partments so covered and an adjoining compartment.

10 In testimony that I claim the foregoing I have hereunto set my hand at Milwaukee, in the county of Milwaukee and State of Wisconsin.

ADELMER A. BISHOP.
